UNITED STATES PATENT OFFICE.

HARRY B. PALMER, OF NEW YORK, N. Y., ASSIGNOR TO MILTON BRADLEY COMPANY,
OF SPRINGFIELD, MASSACHUSETTS, A CORPORATION OF MASSACHUSETTS.

GAME APPARATUS.

1,098,680.

Specification of Letters Patent.

Patented June 2, 1914.

Application filed June 18, 1913. Serial No. 774,436.

To all whom it may concern:

Be it known that I, HARRY B. PALMER, a citizen of the United States of America, residing at New York, in the county and State of New York, have invented certain new and useful Improvements in Game Apparatus, of which the following is a specification.

This invention relates to a game which 10 I propose to call "Traparat," and which may be played by any number of persons up to four. Among its important advantages are the facts that it is extremely cheap and simple and cannot be attended by any danger even if played by the very smallest children, yet, at the same time, it is amusing and exciting and permits the acquisition of a good deal of skill in its practice.

In the drawings, Figure 1 is a plan view 20 of the game; Fig. 2 is a side elevation thereof, partly broken out. Fig. 3 is a perspective view thereof. Fig. 4 is a detail view of my propelling device.

The game comprises a board *a* boxed at 25 its sides, as shown at *b*, and having, substantially in its center, a revolute trap-member *c* provided with apertures *d*, as clearly shown in the drawings. The apertures *d* are in the form of a channel going 30 all the way through the member *c*, as shown by dotted lines in Figs. 1 and 2. Mounted in the member *c* is an upright post *d'* carrying an arm *e* from which is suspended, by the cord *f*, the ball *g*. Fastened to two of 35 the side walls *b* of the board are the uprights *h* connected at their tops by a cross-rod *i*, which has a bearing for the rod *d'*. A spiral spring *k* attached at one end to the rod *d'* and at the other to the cross-rod *i*, 40 provides the motive power for the revolute element *c*. At either end of the board is a propelling device *l* adapted to propel a ball *m* from a socket *n* provided immediately in front of the propelling device in the direction of the revolute trap-member *c*.

To play the game, the rod *d'* is turned, winding up the spring *k* to the extent desired. When the rod is thereafter released, it will turn to rotate back under the impulse 50 of the spring *k*. This return rotation of the rod *d*, however, will be interrupted at intervals because the ball *g*, being radially extended by centrifugal force, will wrap

around the post *h*, interrupting the revolution of the rod *d'* and the member *c* until 55 the ball has unwrapped itself from one of these posts, when the revolution of the member *d'* can continue until the ball wraps itself around the next post, and so on. Thus, it will be seen that the member *c* has a continually and regularly interrupted rotation. The object of the game is to drive the balls 60 *m* into the apertures in the member *c* during the intervals in which these recesses come to rest. Appropriate scoring values 65 are assigned to each successful attempt to get a ball in a recess.

Having now described my invention, but recognizing that many changes and modifications may be made from the specific forms 70 in which I have chosen here to illustrate it without departing from the scope of the invention, which is more truly bounded and defined by the claims hereto appended, I claim,—

1. A game apparatus, comprising a board, a projecting device upon the board, a revolute element having apertures, means to revolve said element, and means to interrupt 75 its revolution.

2. A game apparatus, comprising a board, a plurality of projecting devices upon the board, a revolute element having apertures, a post upon said revolute element, a spring for rotating the post, an arm upon the post 80 carrying an attached ball, and an upright at each side of the board.

3. A game apparatus, comprising a revolute element having apertures with scoring values, means to revolve said element, 90 and means to interrupt its revolution and means arranged to impel a movable device in said apertures and said movable device.

4. A game apparatus, comprising a revolute element having apertures, a spring for 95 revolving said element, a swinging element connected to said revolute element by a flexible connection, and a plurality of posts about which the flexible connection wraps itself as the said element revolves, thereby 100 interrupting its revolution.

HARRY B. PALMER.
